Inventor:
JOSIAH JANUCHOWSKY.
By A. G. Fletcher atty.

UNITED STATES PATENT OFFICE.

JOHN JANUCHOWSKY, OF WEBSTER GROVES, MISSOURI.

REINFORCING AND SEALING DEVICE.

1,394,678.

Specification of Letters Patent. Patented Oct. 25, 1921.

Application filed February 12, 1921. Serial No. 444,333.

To all whom it may concern:

Be it known that I, JOHN JANUCHOWSKY, a citizen of the United States of America, and a resident of Webster Groves, in the 5 county of St. Louis and State of Missouri, have invented certain new and useful Improvements in a Reinforcing and Sealing Device for Boxes and the like, of which the following is a specification.

10 The primary object of this invention is to provide an improved metallic sealing device for cardboard boxes for inclosing the meeting seams of the folding portions of the boxes.

15 Another object of the invention is to provide an arrangement of metallic straps forming part of the construction of a box which is made of cardboard, or of like material, and in which when the box is closed 20 after packing, the tying or meeting ends are secured to one another and sealed.

25 A further object of the invention is to provide a plurality of metallic straps to a cardboard box for covering the meeting edges 25 of the foldable flaps of the box, and securing said straps together in such a manner whereby the heretofore gluing of the foldable flaps for sealing the box ready for shipment is eliminated.

30 Other and further objects will appear in the specification and be specifically pointed out in the appended claims, reference being had to the accompanying drawings exemplifying the invention, and in which,

35 Figure 1 is a perspective view of the box showing this improved reinforcing and sealing device applied thereto.

Fig. 2 is a transverse vertical section taken approximately on the line 11—11 of Fig. 1, 40 a pair of opposing foldable flaps of the box being shown in opened positions.

Fig. 3 is a fragmentary transverse section taken on the line 111—111 of Fig. 1.

Fig. 4 is an enlarged fragmentary perspective view of one of a pair of securing ends of one of the sealing and reinforcing straps.

Fig. 5 is an enlarged fragmentary view of a securing end of another metallic strap.

50 Fig. 6 is an inverted fragmentary view of the intersecting portions of the pair of metallic straps used in connection with this improvement.

Referring to the accompanying drawings, 55 and especially Figs. 1 and 2, a box 1 is shown which is constructed of corrugated

cardboard and having the usual side walls 2, end walls 3 and bottom wall 4, the end walls 3 each bearing the usual foldable flaps 5 while the side walls 2 have the usual closure 60 flaps 6 extended therefrom.

Boxes of this character, after being filled and prepared for shipment, and upon closing the flaps 5 and 6, are sealed by said flaps 6 being glued to the flaps 5 and the 65 meeting edges 7 of the flaps 6 being sealed by gluing a paper or canvas strip thereto; it has been found, however, that such sealing of the flaps 5 and 6 can be broken open and articles removed from the box and the flaps resealed, 70 and when the box or package has reached its destination, the outside appearance thereof on account of the resealing of the flaps will not disclose to the receiver of the box that it has been tampered with, and the discovery is 75 made after the sealing of the flaps has been broken by the receiver, such discovery being determined by the articles lacking, and it is then a hard matter to prove whether the box 80 was opened in transit, for the opening of the flaps by the receiver thereof destroys the resealing evidence.

The main theme of this invention is therefore to provide an accessory to a box or container of the above character wherein the 85 sealing of the flaps thereof can be eliminated, and in which means are provided whereby any tampering of the container by an unauthorized person can be readily detected previous to the opening of the container.

In this connection, a pair of metallic straps 8 and 9 are provided, said straps being secured to each other intermediate of their ends by the interlacing as designated 95 at 10 Fig. 6, the strap 8 being extended across the bottom 4 of the box, having a pair of portions 11, each of said portions being engaged against and secured to the outside of a respective side wall 2 of the box by the 100 stamped out portions 12, which are engaged and crimped to each side wall, the extended ends 13 of each of the portions 11 each being provided with a stamped out tongue portion 14 having an opening 15, said portion 13 being adapted to extend over a respective closure flap 6, the extremity 16 thereof being undercrimped against each of the flaps.

The strap 9 after being extended longitudinally across the bottom 4, is provided with a pair of upwardly extended portions

17 each being provided with a stamped out portion 18 for engagement with each of the end walls 3, the ends 19 of the said strap 9 adapted to be extended horizontally and 5 longitudinally over the meeting edges 7 of the closure flaps 6, the extremities 20 of each of the said portions 19 bearing a pair of slots 21.

These straps 8 and 9 are made from relatively thin material, and when secured to a cardboard box form a part thereof and after the box has been filled with articles to be shipped, the end flaps 5 are folded downwardly as shown in Fig. 2, then the closure 15 flaps 6 are folded down over the end flaps 5 leaving the tongues 14 of the portions 13 of the strap 8 adjacent and in alinement with each pair of openings formed in the portions 19 said portions 19 being pressed 20 downwardly in succession wherein the pair of tongues 14 will enter within each respective pair of slots 21 of the portions 19 and when said portions 19 are held in their coöperable positions relative to the tongues 25 14 a sealing wire 22 is engaged and passed through the openings 15 of said tongues, the looping of said wire being completed and held in engagement with said tongues by the seal 23.

30 The securing arrangement of the metallic straps 8 and 9 to a cardboard box not only provides a seal thereto as just described, but also provides a reinforcement to the walls of the box against bulging pressure of the 35 contents of the box.

What I claim and desire to secure by U. S. Letters Patent is:

1. A device for covering and providing a seal to the adjacent meeting edges of the 40 foldable closure flaps of a cardboard box, comprising a pair of metallic straps adapted to be bound around the box over the respective ends and sides thereof, one of said straps being of a length wherein the ends thereof will meet and overlap, said other strap at each of its ends having a portion under engaging a respective foldable flap, means provided for securing said strap ends to each other comprising a tongue formed 45 on each end of one of said straps, each end of said other strap bearing a pair of slots for the reception of said tongues, and a securing element engaging said tongues for preventing their being disengaged from the slots of said other strap ends.

2. A device for covering and providing a seal to the adjacent meeting edges of the 50 foldable closure flaps of a cardboard box, comprising a pair of metallic straps adapted 60 to be bound around the box over the respective ends and sides thereof each having a stamped out portion for securing it to said box, one of said straps being of a length wherein the ends thereof will meet and overlap, said other strap at each of its ends

having a portion under engaging a respective foldable flap, means provided for securing said strap ends to each other comprising a tongue formed on each end of one of said straps, each end of said other strap bearing 70 a pair of slots for the reception of said tongues, and a securing element engaging said tongues for preventing their being disengaged from the slots of said other strap ends.

3. A device for covering and providing a seal to the adjacent meeting edges of the foldable closure flaps of a cardboard box, comprising a pair of metallic straps adapted to be bound around the box over the respective 80 ends and sides thereof each having a stamped out portion which is crimped into engagement with a respective vertical wall of said box, one of said straps being of a length wherein the ends thereof will meet 85 and overlap, said other strap at each of its ends having a portion under engaging a respective foldable flap, means provided for securing said strap ends to each other comprising a tongue formed on each end of one 90 of said straps, each end of said other strap bearing a pair of slots for the reception of said tongues, and a securing element engaging said tongues for preventing their being disengaged from the slots of said other strap 95 ends.

4. The combination of a receptacle having a pair of closure flaps, a strap adapted to be bound around said receptacle wherein the ends thereof each bearing a pair of slots will overlap one another, and there being a tongue carried by each of said closure flaps each adapted to enter alining slots of said strap ends when said ends are overlapped, and securing means for engagement with 100 said tongues for preventing said strap ends being separated.

5. A device for covering and providing a seal to the foldable closure flaps of a cardboard box, comprising a pair of metallic 110 straps adapted to be bound around the box over the respective ends and sides thereof, one of said straps being of a length wherein the ends thereof will meet and overlap, the other said strap at each end having a portion under engaging a meeting edge of a respective foldable flap, and there being means provided for securing said strap ends to each other.

6. A device for covering and providing a seal to the foldable closure flaps of a cardboard box, comprising a pair of metallic straps adapted to be bound around the box over the respective ends and sides thereof, one of said straps being of a length wherein the ends thereof will meet and overlap, there being means provided for securing said strap ends to each other comprising a tongue formed on each end of one of said straps, each end of said other strap having a pair 125 130

of slots for the reception of said tongues, and a securing element engaging said tongues for preventing them being disengaged from the slots of said other strap ends.

5 7. The combination of a receptacle having a pair of foldable closure flaps, a strap portion extended upwardly from opposing walls of the receptacle, there being means carried by each of said closure flaps for interengagement with each of said strap portions, and a securing element for coöperation with said interengaging portions for preventing said strap portions from becoming separated.

10 8. The combination of a receptacle having a pair of closure flaps, a strap adapted to be bound around said receptacle wherein the ends thereof each bearing a pair of slots will overlap one another and the meeting edges of said closure flaps, lengthwise thereof, and 15 there being a tongue carried by each of said closure flaps each adapted to enter alining

slots of said strap ends when said ends are overlapped, and securing means for engagement with said tongues.

9. The combination of a receptacle having 25 a pair of foldable closure flaps, and means for holding said flaps in closed positions comprising a metallic strap portion borne by each of said flaps, each of said strap portions bearing a tongue, strap extensions arranged 30 at right angles to said strap portions each being secured to the end walls of the receptacle, each of said strap extensions being provided with a pair of adjacent slots, said strap extensions when engaged overlap- 35 pingly lengthwise of the meeting edges of said flaps adapted to have the slots borne thereby engage respective tongues of said strap portions, and a securing member engaging said tongues for preventing their 40 being disengaged from said slots.

JOHN JANUCHOWSKY.
